DESIGN FOR A SCARF

Edgar C. Hyman, New York, N. Y.

Application October 15, 1936, Serial No. 65,311

Term of patent 3½ years

To all whom it may concern:

Be it known that I, Edgar C. Hyman, a citizen of the United States of America, residing in city of New York, county of New York, and State of New York, have invented a new, original, and ornamental Design for a Scarf, of which the following is a specification, reference being had to the accompanying drawing, forming part thereof.

The figure is a face view of a half section of the scarf showing my new design, the other section being identical with that here disclosed arranged in proper relation to complete the scarf.

I claim:

The ornamental design for a scarf, substantially as shown and described.

EDGAR C. HYMAN.
